DRAFTING INSTRUMENT HOLDER OR
SIMILAR ARTICLE

John A. Fretz, Jr., Philadelphia, Pa.

Application June 15, 1951, Serial No. 15,565

Term of patent 7 years

(Cl. D74—1)

To all whom it may concern:

Be it known that I, John A. Fretz, Jr., a citizen of the United States of America, and residing at Philadelphia, in the State of Pennsylvania, have invented a new, original, and ornamental Design for a Drafting Instrument Holder or Similar Article, of which the following is a specification, reference being had to the accompanying drawings, forming part thereof.

In the drawings:

Figure 1 is a view in top plan of a drafting instrument holder or similar article embodying my new design;

Figure 2 is a view in front elevation; and

Figure 3 is a view in side elevation, the opposite side being similar.

I claim:

The ornamental design for a drafting instrument holder or similar article, substantially as shown and described.

JOHN A. FRETZ, JR.
